BRIDGE PIECE FOR A GUITAR OR THE LIKE

James Ormston Burns, Buckhurst Hill, England, assignor
to Ormston Burns Limited, Stamford Hill, London,
England, a British company

Filed Oct. 23, 1963, Ser. No. 77,128

Claims priority, application Great Britain Apr. 25, 1963

Term of patent 14 years

(Cl. D56—1)

FIG 1

FIG 3

FIG 2

FIG 5

FIG 4

FIG 7

FIG 6

FIG. 1 is a perspective view of a bridge piece for a guitar or the like embodying my new design;

FIG. 2 is a side elevational view;

FIG. 3 is another side elevational view showing the side opposite that shown in FIG. 2;

FIG. 4 is a front elevational view;

FIG. 5 is a rear elevational view;

FIG. 6 is a top plan view; and

FIG. 7 is a bottom plan view thereof.

I claim:

The ornamental design for a bridge piece for a guitar or the like, substantially as shown.
